CLAIM

The ornamental design for a bottle for fluid medicines, as shown and described.

DESCRIPTION

FIG. 1 is an isometric view of a bottle for fluid medicines showing my new design;

FIG. 2 is a side elevational view, the opposite side being the same in appearance;

FIG. 3 is a view looking from the right of FIG. 2, the opposite side being the same in appearance;

FIG. 4 is a top plan view; and

FIG. 5 is a bottom plan view.

FIG. 1

FIG. 2

FIG. 3

FIG. 4

FIG. 5
